UNITED STATES PATENT OFFICE.

CLARENCE HARRY FORNEY, OF JERSEY CITY, NEW JERSEY, ASSIGNOR TO FORNEY
FIBRE COMPANY, OF JERSEY CITY, NEW JERSEY.

SPOOL-HEAD.

1,388,635.

Specification of Letters Patent. Patented Aug. 23, 1921.

Application filed August 6, 1919. Serial No. 315,585.

To all whom it may concern:

Be it known that I, CLARENCE H. FORNEY, a citizen of the United States, residing at Jersey City, in the county of Hudson and

5 State of New Jersey, have invented certain new and useful Improvements in Spool-Heads, of which the following is a specification.

The main object of my invention is to provide a disk-shape spool head of card board or other fibrous material which will have its outer edge hardened whereby said outer edge can be finished, for example by sand 10 papering, so as to present a smooth surface and at the same time the head will be made more rigid and stronger than if the outer edge were not hardened. For this reason, spool heads made in accordance with my present invention are particularly well suited 15 for use on spools for containing silk where it is necessary to provide spool heads of maximum rigidity with a minimum amount of weight.

This object, and other advantageous ends 20 which will be described hereinafter, I attain in the following manner, reference being had to the accompanying drawing in which

Figure 1 is a face view of a disk-shape card board spool head showing the same before the outer or peripheral edge is hardened,

Fig. 2 is a view of similar nature to Fig. 1 showing the same after the outer or peripheral edge has been hardened in accordance 25 with my invention,

Fig. 3 is a transverse section taken on the line 3—3 of Fig. 2, and

Fig. 4 is a front elevation of a spool made up of disk-shaped card board heads having 30 their peripheral edges hardened in accordance with my invention and showing in dot-and-dash lines the connecting core between the heads.

Referring to the drawing, the outer peripheral edge portion 5 of the disk-shaped card board spool head 6, as shown in Fig. 1, is treated for example by applying a solution of linseed oil thereto and baking the same until the desired hardness is obtained.

50 This hardened edge is indicated at 7 in Figs. 2, 3 and 4.

The disk-shaped head is preferably pro-

vided with a central hole 8 and two of these heads can be joined by a core 9, as shown in dot-and-dash lines in Fig. 4, to produce a 55 spool.

It will be understood that a disk-shaped card board spool head without having my improved hardened edge is incapable of being finished on the outer edge portion to 60 the degree of smoothness possible when the edge portion is hardened as above described, for the reason that the fibers of the card board do not hold together with sufficient strength to permit the application of sand 65 paper or a tool thereto without breaking apart. However, by hardening the outer edge portion as above described, the fibers at the outer edge portion are firmly bound together in a compact mass and as such can be 70 operated upon by sand paper or a tool of any character to provide a perfectly smooth finish. Furthermore, the hardened portion being circular and extending completely around the disk will greatly strengthen the 75 disk without adding undesirable increased weight as above noted. In addition to this the core 9 can be secured by gluing or other suitable means and as such the glue or other binding means will penetrate the central unhardened portion of the disk so as to provide a secure binder for the heads to the core.

While I have described a certain manner of hardening the outer edge portion of my 85 improved spool head, it will be understood that any other process of hardening may be used without departing from the spirit of my invention, hence I do not limit myself to the precise manner of hardening set forth 90 but consider that I am at liberty to make such changes and alterations as fairly come within the scope of the appended claims.

Having thus described my invention, what I claim as new and desire to secure by Letters Patent is:—

1. A fibrous disk shape spool head having its outer integral edge portion hardened and other integral portions adjacent its axis comparatively soft; substantially as described.

2. A fibrous disk shape spool head having its outer integral edge portion hardened and its central unhardened portion provided

with a hole whereby a spool core can be secured thereto; substantially as described.

3. A fibrous disk shape spool head having its outer integral edge portion hardened and its central integral portion unhardened; substantially as described.

In testimony whereof I have signed my

name to this specification in the presence of two subscribing witnesses.

CLARENCE HARRY FORNEY.
